UNITED STATES PATENT OFFICE.

FRIEDRICH VOSS, OF BURG, IN DITHMARSCHEN, GERMANY.

BEER-GLASS TRAY.

No. 821,208.

Specification of Letters Patent.

Patented May 22, 1906.

Application filed November 9, 1905. Serial No. 286,458.

To all whom it may concern:

Be it known that I, FRIEDRICH VOSS, a citizen of the German Empire, and a resident of Burg, in Dithmarschen, Province of Sleswick-Holstein, Germany, have invented certain new and useful Improvements in Beer-Glass Trays, of which the following is a specification.

This invention relates to a beer-glass tray which absorbs the drippings and conveys the same to a receiving-trough, so that cleanliness is insured.

In the accompanying drawings, Figure 1 is a plan, partly broken away, of my improved beer-glass tray. Fig. 2 is a cross-section on line A B, Fig. 1; and Fig. 3, a side elevation.

The letter *a* indicates a base-plate composed of a raised central section *a*², a downwardly-extending upright flange *a'*, and an upwardly - curved rim *b*. Thus there is formed between the parts *a'* and *b* an annular trough which surrounds the central raised section *a*² of the plate. The top of raised section *a*² is provided with radial grooves *f*, communicating with alined grooves *f'* of flange *a'*. The parts *a*² *a'* are covered by an absorbent cloth *c*, held to the plate *a* by means of a ring *d*, surrounding flange *a'*. In order to securely connect the parts, the ring *d* is provided with an inwardly-extending bead *d'* opposite a corresponding recess of flange *a'*.

Perforations *o* in ring *d* permit the escape of the liquid, which trickles through the cloth and passes along the grooves *ff'* through the openings *o* into the trough. If the cloth is

to be renewed, it may be readily detached by first removing the ring.

What I claim is—

1. In a beer-glass tray, a plate having a raised grooved section, an upright flange extending from the edge of said raised section to the bottom of the plate, and a rim surrounding said plate, combined with a cloth covering the raised section and the upright flange, and means for securing the cloth to said flange, substantially as specified. 40

2. In a beer-glass tray, a plate having a raised grooved section, a grooved upright flange extending from the edge of said raised section to the bottom of the plate, and a rim surrounding said plate, combined with a cloth covering the raised section and the grooved flange, and a ring that engages the cloth and surrounds the grooved flange, substantially as specified. 50

3. In a beer-glass tray, a plate having a raised grooved section, a grooved upright flange extending from the edge of said raised section to the bottom of the plate, and a rim surrounding said plate, combined with a cloth covering the raised section and the grooved flange, and a perforated ring that engages the cloth and surrounds the grooved flange, substantially as specified. 55 60

Signed by me at Hamburg, Germany, this 24th day of October, 1905.

FRIEDRICH VOSS.
